Fig. 2

Fig. 1 is a side view of my design for a walking stick for the left hand;

Fig. 2 is a similar view showing the opposite of the handle; and

Fig. 3 is a front elevation of the handle.

Fig. 4 is an end view of my walking stick looking from the right of Fig. 1; and

Fig. 5 is a side elevational view thereof.

The handle for the right-hand looks exactly the same except in reverse.

The dominant features of my design are shown in full lines.

I claim:

The ornamental design for a walking stick, substantially as shown and described.
